UNITED STATES PATENT OFFICE.

LE ROY S. WHITE, OF ENDICOTT, NEW YORK.

FOLDING UMBRELLA.

1,043,651.

Specification of Letters Patent.

Patented Nov. 5, 1912.

Application filed March 16, 1912. Serial No. 684,139.

To all whom it may concern:

Be it known that I, LE ROY S. WHITE, a citizen of the United States, residing at Endicott, in the county of Broome and State 5 of New York, have invented certain new and useful Improvements in Folding Umbrellas; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to new and useful improvements in folding umbrellas and the object in view is to produce a simple and efficient device of this nature so arranged 20 that the ribs may telescope one within another and the stick which is made up of sections disconnected, thereby reducing the umbrella to a small compass.

The invention is illustrated in the accompanying drawings, in which:—

Figure 1 is a side elevation showing the manner of connection of a brace and rib section. Fig. 2 is an enlarged detail sectional view showing the manner of holding the telescoping rib extended. Fig. 3 is a detail perspective of one of the braces, and Fig. 4 is a perspective view of a rib shell and spring catch thereon.

Reference now being had to the details 35 of the drawings by letter, A designates an umbrella stick which in the present instance is shown made of two parts having threaded connections with each other. The usual runner B is mounted upon the stick and to 40 which a brace C is pivoted at one end and its other end is pivotally connected to a pin passing through an aperture D' formed in a lug D upon a telescoping rod D², a detail view of which is shown in Fig. 2 of the 45 drawings. E designates a hollow section of one of the ribs pivoted at E' to the notch member F. Said rib section E is provided with a longitudinal slot H, adjacent to one end of which is a resilient finger K 50 having an offset or recess K' therein. Said rib section D² telescopes within the section

E and the shank portion of the lug D is movable in said slot. A lateral projection D³ upon the lug is adapted to frictionally contact with the under surface of the resilient finger K and which latter will yield to allow said lateral projection to pass into the recess or offset K', thereby tending to hold the two sections of the rib extended.

While in the drawings I have shown but 60 a single pair of telescoping ribs, it will be understood that all are to be similarly constructed and pivotally connected to the runner. When it is desired to fold the umbrella, the runner is moved down upon the 65 stick and the sections D² telescoping within the shell sections E and the stick disconnected to reduce its length, thereby making an umbrella substantially half the length of the usual umbrella and in a compact and 70 convenient form for transportation in valises, etc.

When it is desired to extend the umbrella, the sections D² are withdrawn and automatically locked in the position shown in 75 Fig. 1 of the drawings.

What I claim to be new is:—

A folding umbrella comprising a stick, rib sections telescoping one within the other, one of said sections being longitudinally 80 slotted, a lug at the end of the inner of the telescoping sections and movable within said slot and provided with an angled projection, said slotted section having an integral resilient finger at one end of said 85 slot and which finger is provided with an offset opposite the end of the slot, the free portion of the finger adjacent to its offset being in a plane parallel with the slot and projected over the edge thereof, the offset 90 provided for the reception of the angled projection of said lug, the face of the lug being adapted to frictionally engage that portion of the finger which is parallel to the edge of the slot, affording means for holding the rib sections extended, as set forth.

In testimony whereof I hereunto affix my signature in the presence of two witnesses.

LE ROY S. WHITE.
